BUFFER WHEEL

John H. McGrady and Westly R. Cypher, Fremont, Ohio

Application June 17, 1932. Serial No. 617,912

8 Claims. (Cl. 51—190)

This invention relates to improvements in buffer wheels of the type generally made of some pliable material, such as canvas, muslin, flannel, soft felt, or the like.

5 The primary object of the present invention is to provide a ventilated buffer wheel which can be rotated at high speed and still do its work without excessive heating.

Another object is to provide a buffer wheel that 10 can be used very efficiently in concave articles or inside of cylindrical articles, on account of the flexibility and resiliency of such wheels. The design and construction of the wheel are such that it can be made as flexible or rigid as required 15 for most any class of work, or any finish that can be obtained by buffing.

A further object is to supply a buffering wheel which can be made without waste of materials, and one which is much more durable than the 20 wheels heretofore known.

A still further object is to supply a buffering wheel with recesses formed therein for retaining compounds, such as lubricants or abrasives used in the process of polishing, buffering or the like.

25 With the foregoing objects outlined and with other objects in view which will appear as the description proceeds, the invention consists in the novel features hereinafter described in detail, illustrated in the accompanying drawings, 30 and more particularly pointed out in the appended claims.

In the drawings,

Fig. 1 is a plan view of the disk which forms the body of the wheel.

35 Fig. 2 is a similar view with alternate sectors of the disk bent upwardly to form a cylinder at the central portion of the disk.

Figs. 3 and 4 are edge views respectively of the disks shown in Figs. 1 and 2.

40 Fig. 5 is a perspective view of a skeleton ring or reinforcement which is incorporated in the wheel during the manufacture of the same.

Fig. 6 is a view like Fig. 4, but with the skeleton ring slipped over the cylindrical portion of the 45 disk.

Fig. 7 is an edge view of the disk shown in Fig. 6, after the bent sectors have been returned to original position.

50 Fig. 8 is a plan view of the structure shown in Fig. 7.

Fig. 9 is a view similar to Fig. 7 after the side disks have been secured to the body and skeleton ring.

55 Fig. 10 is a perspective view of one of the side disks.

Figs. 11 to 15 inclusive are plan views of a completed unit, and illustrating various ways of stitching or otherwise securing the parts together.

Referring to the drawings, 16 designates a disk which may be made of any suitable textile or 60 fibrous material, such as felt or the like, provided with a central aperture 17 and also provided with radial slits 18 extending substantially from the center area to the outer edge of the disk, and forming a plurality of sectors 19. After the disk has been slitted, alternate sectors 19 of the same are bent upwardly into substantially cylindrical form, as shown in Figs. 2 and 4. Then a skeleton ring 20, formed of layers of textile or other suitable pliable material, is slipped over the bent 70 sectors, as shown at 21 in Fig. 6. Subsequently, the bent sectors are returned to original position, as shown in Figs. 7 and 8, so that the disk is again flat and the ring 20 assumes a zig-zag shape, or forms a zig-zag ring about the hub 22 of the disk. 75

Then side disks 23 of layers of some pliable material, such as muslin or the like, are placed at opposite sides of the disk, and the parts are all stitched or otherwise secured together in any suitable way. For example, radial rows of stitching 24 may be used, as shown in Fig. 11, or V-shaped 80 lines of stitches 25 may be used, as in Fig. 12. Fig. 13 shows circular rows of stitches 26, while in Fig. 14 the line of stitching 27 is of spiral shape. Fig. 15 shows parallel rows of stitching 28. 85

Obviously, any preferred form of stitching may be used, or combinations of the same may be employed, and if desired, similar stitching may be used on the units shown in Figs. 7 and 8 before the side disks 23 are attached. 90

Due to the zig-zag form of the skeleton ring, recesses 29 are provided within the unit, and these recesses may be used to retain various compounds, lubricants, abrasives, etc.

Manifestly, a wheel of any desired width or 95 thickness may be made by placing the finished units side by side on the buffer wheel shaft.

While we have shown the disk 16 made of twelve sectors 19, nevertheless it will be understood that there is no restriction as to the number which may be employed, as we have found in practice that disks made with four to sixteen sectors are very satisfactory.

It is also possible to make the disk from a plurality of pieces of material, stitching or otherwise 105 securing them together. In this way the material cut to form the center of ring 20 (Fig. 5) can be utilized.

From the foregoing it is believed that the construction and advantages of the invention will be 110

readily understood by those skilled in the art, and it is apparent that changes may be made in the details disclosed without departing from the spirit of the invention, as expressed in the claims.

5 What is claimed and desired to be secured by Letters Patent is:

1. A buffer wheel unit comprising a disk of pliable material provided with slits, a skeleton ring associated with said disk, certain portions of the disk being positioned at one side of said ring and other portions of the disk being arranged at the opposite side of the ring, and means securing the ring and disk together. 80
10 2. A buffer wheel unit comprising a disk of pliable material provided with radially arranged slits extending from its hub portion to its periphery, a skeleton ring associated with said disk, certain portions of the disk being positioned at one side of said ring and other portions of the 85
15 disk being arranged at the opposite side of the ring, and means securing the ring and disk together. 90
20 3. A buffer wheel unit comprising a disk of pliable material having slits extending from its hub portion to its periphery, a skeleton ring associated with the disk, certain portions of the disk being positioned at one side of said ring and other portions of the disk being arranged at the 95
25 opposite side of the ring, and means securing the ring and disk together, said ring being of zig-zag form circumferentially. 100
30 4. A buffer wheel unit comprising a disk of pliable material having slits extending from its hub portion to its periphery, a skeleton ring associated with the disk, certain portions of the disk being positioned at one side of said ring and other portions of the disk being arranged at the opposite side of the ring, and means securing the ring and disk together, the last mentioned means including stitching. 105
35 5. A buffer wheel unit comprising a disk of

flexible material or the like, having slits extending from its hub portion to its periphery, a skeleton ring associated with said disk, certain portions of the disk being positioned at one side of said ring and other portions of the disk being arranged at the opposite side of the ring, and means securing the ring and disk together, the last mentioned means including side disks and means securing the side disks to the ring and disk. 80

6. A buffer wheel unit comprising a disk of flexible material or the like, having slits extending from its hub portion to its periphery, a skeleton ring associated with said disk, certain portions of the disk being positioned at one side of said ring and other portions of the disk being arranged at the opposite side of the ring, and means securing the ring and disk together, the last mentioned means including stitching extending from the hub portion to the peripheral portion of the disk. 85

7. A buffer wheel unit comprising a disk of pliable material or the like, provided with radially disposed slits forming sectors, a skeleton ring of flexible material incorporated within the disk, certain of the sectors being positioned at one side of said ring, and alternate ones of the sectors being arranged at the opposite side of the ring, and means securing the sectors and ring together. 90

8. A buffer wheel unit comprising a disk of pliable material or the like, provided with radially disposed slits forming sectors, a skeleton ring of relatively soft flexible material incorporated within the disk, certain of the sectors being positioned at one side of said ring, and alternate ones of the sectors being arranged at the opposite side of the ring, and means securing the sectors and ring together, the last mentioned means including side disks and lines of stitching connecting the disks and ring. 105
